ATTORNEY

UNITED STATES PATENT OFFICE.

IRA EDWARD SMITH, OF STOCKTON, CALIFORNIA.

ELECTRIC SWITCH.

Application filed April 17, 1922. Serial No. 553,962.

To all whom it may concern:

Be it known that I, IRA E. SMITH, a citizen of the United States, residing at Stockton, county of San Joaquin, State of California, have invented certain new and useful Improvements in Electric Switches; and I do declare the following to be a full, clear, and exact description of the same, reference being had to the accompanying drawings, and to the characters of reference marked thereon, which form a part of this application.

This invention relates to improvements in electric switches, and particularly to a type of thermostatically or pressure operated switch to be used to control the generation of heat, steam, or other pressure.

The principal object of this invention is to provide a switch controlled as above stated, which is particularly adapted to be interposed in a motor circuit, the motor being in turn connected with a rheostat, and which is so arranged and constructed that until the heat or pressure arrives at a certain point, by means of the motor (which operates to produce the heat or pressure) the circuit will be closed through the switch to the motor direct, allowing the latter to run at full or normal speed. When the aforementioned heat or pressure point is passed, the circuit direct to the motor will be broken, and the current instead will be passed to the motor through the rheostat or other resistance slowing down the motor; while at a still higher heat or pressure point the circuit will be broken entirely, stopping the motor, and will not again be closed until the heat or pressure is reduced to the original point.

This switch is therefore adapted to be used not only with the above mentioned oil burning system to produce steam or hot air pressure, but with air compressing and water pumping systems operated by electric motors.

Another object is to provide an adjustment means on the switch to provide for the cutting in of the rheostat, or the breaking of the circuit, with whatever degree of heat or pressure may be desired in any particular case.

Another object is to provide a positive acting switch which will function and be actuated with, but an extremely small amount of power being necessary.

A further object of the invention is to

produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Fig. 1 is a side view of my improved switch showing the same installed in connection with an ordinary form of steam or air pressure gage coil.

Fig. 2 is a front view of the switch detached, showing the same in its normal or at-rest position.

Fig. 3 is a similar view, showing one set of the contacts broken.

Fig. 4 is a similar sectional view, showing all the contacts broken.

Fig. 5 is an enlarged sectional view of a block showing a contact-point construction.

Fig. 6 is a wiring diagram, showing my switch interposed in circuit with a motor and rheostat.

Referring now more particularly to the characters of reference on the drawings, the numeral 1 denotes a rigid and vertical back member, provided with top and bottom projections or flanges 2 and 3 respectively. Slidable through metal bushings 2^a set in said flanges is a pin or stem 4 preferably having on its lower end a weight 5.

Between the flanges 2 and 3 are a pair of blocks 6 and 7, the upper one 6 being firmly but adjustably fixed to the stem 4, which passes therethrough, while the lower one 7, through which the stem also passes, is frictionally but yieldably held to the stem by means of spring-pressed balls 8 or similar friction means mounted in said block, the pressure of the springs being adjustable, whereby the pressure of the balls against the stem may be varied.

The members 1, 2, 3, 6 and 7 are preferably made of an insulating material, such as bakelite, which besides being a good insulator does not warp or change its shape with varying conditions of cold, heat and moisture, and therefore the switch will work freely and well under any such conditions. The blocks 6 and 7 are normally spaced apart somewhat in order to allow

for separable contact points 9 and 10 being placed between the adjacent surfaces of the blocks 6 and 7 and for similar points 11 and 12 being placed between the adjacent faces of the blocks 7 and flange 3 respectively.

10 A binding post 13 is provided on the block 6 and connected to the contact 9, another post 14 on the block 7 is connected in common to the points 10 and 11, and still another post 15 on the flange 3 is connected to the contact 12 thereof.

15 The contact points 9, 10, 11 and 12 are preferably made of tungsten metal with absolutely flat contacting surfaces set in short cap-screws A which in turn are screwed into threaded metal bushings B connected to the binding posts and are set and moulded in the flange 3 and blocks 6 and 7. This 20 construction makes repairs and replacements easy and gives a solid, well connected member.

25 Adjustably mounted in the upper flange 2 is a stop pin 16, which projects freely through the block 6 but is adapted to abut against the block 7 when the latter is raised a predetermined distance.

30 The stem 4 is preferably notched or recessed as at 17 so as to form a definite seat for the adjustable spring pressed balls 8 so that blocks 6 and 7 are forced together and spring-locked, when blocks 6 and 7 are in their lowermost position, in order to insure positive contact of the points 9 and 10 when 35 the blocks 6 and 7 are raising due to the expansion of the pressure or thermostatic means.

40 The upper end of the stem 4 above the switch is adjustably connected to the flexible coil or loop 18 of an ordinary pressure gage (see Fig. 1), by means of a lug 19 on the free end of the coil, through which an adjustable screw 20 freely passes, this screw being threaded into flexible jointed blocks 45 21 to which the stem 4 is fixed. The screw preferably has a pin 22 projecting therethrough, and normally a certain distance above the lug 19, so that the latter and the coil may have a certain and predetermined 50 amount of travel before any raising movement is imparted to the stem and blocks, the flexibly jointed blocks permitting movement of the end of the loop 18 not in a direct line with the stem 4 without binding the latter.

55 The switch itself is fixed on a rigid bracket 1^a. To interpose the switch in a circuit, a main line wire 23 leads to the post 13, a wire 24 leads from the post 14 through the rheostat or resistance 26 to the motor 27 through a wire 28 beyond said resistance, while another wire 25 leads from the post 15 to a connection with the wire 28 leading direct to the motor. The other lead 29 to the motor is connected to the main line 30 in common with the wire 23.

In operation, the stem and blocks will be held inactive until the pressure in the member 18 has expanded the same so that it bears against the pin 22, which extent of expansion may be regulated as will be evident, by adjusting the screw 20 to suit. During this period, the current is passing direct to the motor through the wires 23 and 25, for even though the resistance circuit is also closed, the current will follow the path 75 of least resistance.

Further expansion of the gage coil will separate the contacts 11 and 12, forcing the current to travel through the wires 23 and 24, through the rheostat, slowing down the 80 motor.

This circuit will remain closed until the block 7 strikes against the adjustable stop pin 16, when with any further upward movement of the coil and stem, the block 7 is held from raising therewith, the balls being forced out of their recessed seat 17 in the stem 4 and slipping on the latter, and causing the separating of the contacts 9 and 10, thus breaking the circuit completely.

90 The switch, and its operating mechanism, are preferably enclosed in a suitable housing, so that they are protected from dirt and dampness, as well as possible injury from other causes.

95 From the foregoing description it will be readily seen that I have produced such a device as substantially fulfills the objects of the invention as set forth herein.

100 While this specification sets forth in detail the present and preferred construction of the device, still in practice such deviations from such detail may be resorted to as do not form a departure from the spirit of the invention, as defined by the appended 105 claims.

Having thus described my invention, what I claim as new and useful and desire to secure by Letters Patent is:

110 1. An electric switch comprising a pair of aligned and movable blocks, a fixed flange beyond said blocks, contact points between said blocks and between said flange and the adjacent block, a stem having frictional engagement with the latter block and rigidly fixed to the other block, whereby said blocks will normally move together with the movement of the stem, and means for causing the separation of the blocks after a predetermined movement of the stem.

115 2. An electric switch comprising a pair of aligned and movable blocks, a fixed flange beyond said blocks, contact points between said blocks and between said flange and the adjacent block, a stem having frictional engagement with the latter block and rigidly fixed to the other block, whereby said blocks will normally move together with the movement of the stem, and a stop pin mounted 125 in the fixed member and adapted to abut 130

against the frictionally engaged block after a predetermined movement of said stem and blocks.

3. An electric switch comprising a fixed flange, a pair of independent blocks above said flange, contact points between said blocks and between the flange and the adjacent block, a movable stem projecting through the blocks and fixed to the uppermost one thereof, means between the lower block and stem for causing yieldable engagement of said block and stem, and means for causing said engagement to yield and separate the blocks after a predetermined vertical movement has taken place.

4. An electric switch comprising a flange projecting therefrom, a pair of independent blocks above said flange, contact points between said blocks and between the flange and the adjacent block, a movable stem projecting through the blocks and fixed to the uppermost one thereof, means between the lower block and stem for causing yieldable engagement of said block and stem, and an adjustable and vertically disposed stop pin mounted to project into the path of movement of the lower block after a predetermined movement thereof with the stem.

5. An electric switch comprising a flange projecting therefrom, a pair of independent blocks above said flange, contact points between said blocks and between the flange and the adjacent block, a movable stem projecting through the blocks and fixed to the uppermost one thereof, spring pressed friction members in the lower block yieldably engaging the stem whereby said blocks will move together with the stem, and means for holding the lower block from further movement while permitting the stem and upper block to move.

6. An electric switch comprising a flange projecting therefrom, a pair of independent blocks above said flange, contact points between said blocks and between the flange and the adjacent block, a movable stem projecting through the blocks and fixed to the uppermost one thereof, spring pressed friction members in the lower block yieldably

engaging the stem whereby said blocks will move together with the stem, and a pressure gauge coil connected at its free end to the stem.

7. An electric switch including a back member, upper and lower flanges thereon, independent blocks positioned between said flanges, said back, flanges and blocks being of an insulation material, a stem slidably mounted in said flanges and connected to the blocks, and contact members between the blocks and between one of said blocks and the adjacent flange.

8. An electric switch including a back member, flanges projecting therefrom at both ends, independent blocks positioned between said flanges, said back member blocks and flanges being of an insulation material, metal bushings in said flanges, in alinement with each other, a stem slidably mounted through the bushings and blocks and connected to the latter, and contact members between the blocks, and between one of said blocks and the adjacent flange.

9. An electric switch including a fixed back member, a stem slidably mounted therewith, contact-bearing blocks connected to said stem, and expanding loop connected at one end to a rigid pipe and at the other end to one end of the stem, and a rigid bracket mounted on the pipe and supporting the back member of the switch.

10. An electric switch including a fixed back member, a stem slidably mounted therewith, contact-bearing blocks connected to said stem, an expanding loop fixed at one end and free at the other, said latter end being adjacent the outer end of the stem, swivel jointed blocks connected to that end of the stem, a lug on the adjacent end of the loop normally resting on the outermost block, and an adjustable member secured in said block and passing freely through the lug and adapted to be engaged by the latter after a certain expansion of the loop has taken place.

In testimony whereof I affix my signature.

IRA EDWARD SMITH.
